CLAIM

I claim the ornamental design for a shelf-fixing bracket, as shown and described.

DESCRIPTION

FIG. 1 is a side view of the shelf-fixing bracket showing my design; the opposite side view being a mirror image thereof.

FIG. 2 is a front view thereof;

FIG. 3 is a back view thereof;

FIG. 4 is a top view thereof;

FIG. 5 is a bottom view thereof; and,

FIG. 6 is an upper perspective view thereof.
